CONTINUOUS WEB MANIFOLDING
ASSEMBLYSerial B. Otis, Chicago, Ill., assignor to The
Wallace Press, Chicago, Ill., a corporation of
Illinois

Application January 11, 1940, Serial No. 313,366

8 Claims. (Cl. 282—12)

This invention relates to manifolding assemblies of the continuous web type in which there are superimposed strips or webs of paper printed and arranged to comprise a long series of successive forms separated by transverse lines of severance whereby the individual forms or packs can be torn off from the strip, and having marginal feedband perforations for use in typewriting machines equipped with pin-feed devices whereby the forms and their copies are kept in accurate registration with each other.

The main object of this invention is to provide an improved construction for the transfer strips of such manifolding assemblies whereby inherent compensation is provided for relative differences of contraction and expansion that may result from air conditions or other factors that have a different effect upon the record strips and the transfer strips due to the fact that said strips may be respectively of different kinds and thicknesses of paper.

According to the present usual practice, continuous manifolding form assemblies are made up of a plurality of separate record and copy strips having printed forms in registering relation, and of single form width, or of multiple form width fanfolded on longitudinal lines. In either case the record and copy strips are interleaved with transfer strips usually of carbon paper and the whole assembly is then zigzag folded by creasing it in successively opposite directions on the transverse severance lines between successive forms.

In manifolding assemblies of this kind, especially those which are designed for use in machines having the pin type of feed, the pin-feed devices tend to bring the forms and transfer sheets into registration at their marginal feedband apertures and if the transfer sheets have become displaced by reason of differences of expansion of their substances as compared with that of the record and copy sheets in passage through the typewriting machine, it is important that they be so constructed as to avoid wrinkling and interference with the re-assembly of the pack as it is refolded on the zigzag folds of the record; or if the forms are torn off in individual form-length packs, it is important that the lines of severance of the record, copy and transfer sheets register accurately to facilitate the tearing operation.

It is, therefore, a further object of this invention to provide a structure for the transfer strips that will always assure close registry between the tearing lines of the respective strips, even though

there may have been some shifting of the transfer strip either by expansion or contraction, or by operation of the feeding mechanism.

A specific embodiment of this invention is illustrated in the accompanying drawing in which:

Fig. 1 is a fragmentary top view of a manifolding assembly, partly broken away in such manner as to show the structure of the different layers.

Fig. 2 is a perspective view of such an assembly zigzag folded in a multiple form pack.

Fig. 3 is a fragmentary face view illustrating a modified form of the assembly shown in Fig. 1.

Fig. 4 is a similar view of a further modified form.

In the form shown in Fig. 1, the essentials of such an assembly comprise a record strip 1, a copy strip 2, and an interposed transfer strip 3. There may, of course, be any number of copy strips up to the capacity of the typewriting machine for making simultaneous copies and there may be a corresponding number of transfer strips.

These strips may all be separated from each other, as illustrated in the drawing, or they may be of the well-known fanform type in which one or more of the copy sheets is integral with the record sheet and brought into manifolding relation by being folded on longitudinal lines. The individual record forms that make up the strip 1 are separated by the usual transverse severance lines 4 which are weakened for tearing the forms apart, either by scoring or by a line of closely spaced perforations.

The assembly is provided on one or both of its longitudinal margins with feed-band perforations 5 which are accurately spaced to cooperate with the pin-feed devices of the typewriting machine of any of the many types of machines in which such forms are used.

According to the present invention, the transfer sheet, instead of having a single line of weakness corresponding to the severance lines 4 of the record, has a band 6 or weakened area of considerable width extending across it in approximate registry with each of the severance lines of the record sheet. In the form shown, this band 6 is made up of a plurality of closely spaced lines of weakness extending parallel to each other across the width of the strip and each comprising a series of perforations similar to those which make up the tearing lines of the record sheet. It is, however, preferable to have the perforations in the individual lines of weakness spaced apart at less distance than the width of

the stock that is left between these lines of weakness, so that as the form lengths are torn apart, the transfer sheet will tear on straight lines.

5 It will be seen that there may be expansion, or contraction, or relative shifting of the record sheets and transfer strips to any extent within the limits of the width of this band of weakness without any disturbance to the folding of the assembly 10 on the transverse severance lines of the strip or the tearing of the entire pack throughout its depth in registry with the lines of weakness of the record forms.

15 In the modified form shown in Fig. 3, the feed-band perforations 5.1 in the transfer sheet are substantially larger than the feed-band perforations 5 of the record and copy sheets.

20 In the modification shown in Fig. 4, the transfer strip is made narrower than the record and copy strips so that its side marginal edges 7 will completely clear the pins that engage the feed band apertures 5 of the record strips.

25 It will be understood that details of the construction shown may be altered or omitted without departing from the spirit of this invention as defined by the following claims.

I claim:

30 1. A continuous web manifolding assembly comprising superposed record, copy and transfer traveler strips, said record strip having transverse lines of severance defining individual form lengths, and said transfer strip having, in approximate registration with each said record severance lines, a plurality of closely spaced parallel 35 transverse severance lines.

40 2. A continuous web manifolding assembly comprising superposed record, copy and transfer traveler strips, said record strip having transverse lines of severance defining individual form lengths, and said transfer strip having, in approximate registration with each said record severance lines, a transversely extending area weakened for severance and having a width in the direction of the length of the strips considerably 45 greater than that of said record severance lines.

45 3. A continuous web manifolding assembly comprising superposed record, copy and transfer traveler strips, said record strip having transverse lines of severance defining individual form 50 lengths, and said transfer strip having, in approximate registration with each said record severance lines, a transversely extending area weakened for severance, parallel and coextensive with said transverse lines of severance, and having a

width in the direction of the length of the strips considerably greater than that of said record severance lines.

4. A continuous web manifolding assembly 5 comprising superposed record, copy and transfer traveler strips, said record strip having transverse lines of severance defining individual form lengths, and said transfer strip having, in approximate registration with each said record severance lines, a transversely extending area comprising 10 multiple parallel lines of weakness for transverse severance of the strip, and having a width in the direction of the length of the strips considerably greater than that of said record severance lines.

5. A continuous web manifolding assembly 15 comprising superposed record, copy and transfer traveler strips, certain of said strips having registering rows of marginal feed-band perforations, said record strip having transverse lines of severance defining individual form lengths, and said 20 transfer strip having, in approximate registration with each said record severance lines, a plurality of closely spaced parallel transverse severance lines.

6. A continuous web manifolding assembly 25 comprising superposed record, transfer and copy strips having registering marginal feed-band perforations, said record strip having transverse lines of severance defining individual form lengths, said transfer strip having in approximate 30 registration with one of said record severance lines a plurality of closely spaced parallel weakened lines of severance, parallel and coextensive with such record line of severance, and said transfer strip having feed-band perforations 35 larger than the corresponding feed-band perforations of said record strip.

7. A transfer strip for continuous manifold assemblies for use in writing machines equipped with pin-feed devices, said strip having marginal 40 feed bands arranged to engage such pin-feed devices with provision for a modicum of shifting relative thereto in the direction of length of the strip, and said strip having weakened transverse lines of severance defining individual form 45 lengths and each comprising a plurality of closely spaced parallel lines of weakness.

8. A transfer strip for continuous manifold assemblies, said strip having weakened transverse lines of severance defining individual form 50 lengths and each comprising a plurality of closely spaced parallel lines of weakness.

ERIAL B. OTIS.
